Primary Examiner — Sandra S Snapp*Assistant Examiner* — Katherine Glennon(74) *Attorney, Agent, or Firm* — Cramer Patent & Design, PLLC; Aaron R. Cramer(57) **CLAIM**

The ornamental design for clock hands, as shown and described.

DESCRIPTION

FIG. 1 is a top front left perspective view of an hour hand, a minute hand, and a central pin, the clock hands shown in an assembled configuration, showing my new design;

FIG. 2 is a perspective top rear right view thereof;

FIG. 3 is a left elevation view thereof;

FIG. 4 is a right elevation view thereof;

FIG. 5 is a left elevation view of clock hands, showing the hour and minute hand in a disassembled configuration, with the pin removed for ease of illustration;

FIG. 6 is a right elevation view thereof;

FIG. 7 is a front elevation view thereof;

FIG. 8 is a rear elevation view thereof;

FIG. 9 is a top plan view thereof; and,

FIG. 10 is a bottom plan view thereof.

1 Claim, 9 Drawing Sheets(56)
